US0D1074482S

(12) **United States Design Patent** (10) **Patent No.:** **US D1,074,482 S**
(45) **Date of Patent:** **** May 13, 2025**

(54) **RELEASE LINERS FOR OSTOMY LEAK DETECTION SENSOR**

(71) Applicant: **Hollister Incorporated**, Libertyville, IL (US)

(72) Inventors: **Jonas P. Carlsson**, Chicago, IL (US); **Lauren M. Lattanzi**, Raleigh, NC (US); **Anthony B. Smith**, Durham, NC (US)

(73) Assignee: **HOLLISTER INCORPORATED**, Libertyville, IL (US)

(**) Term: **15 Years**

(21) Appl. No.: **29/878,816**

(22) Filed: **Jun. 28, 2023**

(51) LOC (15) Cl. **24-02**

(52) U.S. Cl. **D24/118**
USPC

(58) **Field of Classification Search**

USPC D10/96; D24/118, 127-129, 186, 200,
D24/108, 168, 170, 187, 206
CPC A61F 2005/4495; A61F 2005/4486; A61F
2005/4483; A61F 5/448

(57) **CLAIM**

The ornamental design for release liners for ostomy leak detection sensor, as shown and described.

DESCRIPTION

FIG. 1 is a front view of release liners for ostomy leak detection sensor embodying our new design;

FIG. 2 is a rear view thereof;

FIG. 3 is a bottom view thereof;

FIG. 4 is a top view thereof;

FIG. 5 is a side view thereof as seen from the right-hand side of FIG. 1;

FIG. 6 is a side view thereof as seen from the left-hand side of FIG. 1;

FIG. 7 is a front, bottom perspective view thereof;

FIG. 8 is a front, top perspective view thereof;

FIG. 9 is a rear, bottom perspective view thereof; and,

FIG. 10 is a rear, top perspective view thereof.

The broken lines shown represent unclaimed subject matter and form no part of the claimed design.

1 Claim, 8 Drawing Sheets
